United States Patent Office

Des. 216,496

Patented Jan. 13, 1970

216,496

KNIFE

James L. Wentzel, Cottage Grove, Minn., assignor to Plastics, Inc., St. Paul, Minn., a corporation of Minnesota

Filed Feb. 14, 1969, Ser. No 15,774

Term of patent 14 years

Int Cl. D7—03

U.S. Cl. D95—3

FIG. 1

FIG. 2

FIG. 3

FIG. 4

FIG. 5

FIG. 6

FIG. 1 is a top edge view of a knife showing my new design.

FIG. 2 is a side elevational view thereof.

FIG. 3 is a bottom edge view thereof.

FIG. 4 is a side elevational view opposite to that of FIG. 2.

FIG. 5 is an enlarged sectional view on the line 5—5 of FIG. 2.

FIG. 6 is an enlarged sectional view on the line 6—6 of FIG. 2.

I claim:

The ornamental design for a knife, as shown.
